CLAIM

The ornamental design for a battery jump starting device, as shown and described.

DESCRIPTION

FIG. 1 is a front, right, and top perspective view of a battery jump starting device, showing our design.

FIG. 2 is a rear, left, and bottom perspective view thereof.

FIG. 3 is a front, left, and top perspective view thereof.

FIG. 4 is a rear, right, and bottom perspective view thereof.

FIG. 5 is a front elevation view thereof.

FIG. 6 is a rear elevation view thereof.

FIG. 7 is a right side elevation view thereof.

FIG. 8 is an enlarged view of detail 8 in FIG. 1.

FIG. 9 is an enlarged view of detail 9 in FIG. 1.

FIG. 10 is an enlarged view of detail 10 in FIG. 1.

FIG. 11 is an enlarged view of detail 11 in FIG. 1.

FIG. 12 is an enlarged view of detail 12 in FIG. 1.

FIG. 13 is an enlarged view of detail 13 in FIG. 1.

FIG. 14 is an enlarged view of detail 14 in FIG. 3.

FIG. 15 is an enlarged view of detail 15 in FIG. 3.

FIG. 16 is an enlarged view of detail 16 in FIG. 3; and,

FIG. 17 is an enlarged view of detail 17 in FIG. 3.

The broken lines shown in the drawings are included for the purpose of illustrating portions of the battery jump starting device that form no part of the claimed design.

Dot-dash broken lines framing portions of the claimed design that are illustrated for enlargements form no part of the claimed design.
